UNITED STATES PATENT OFFICE.

HAROLD A. HART, OF HARTFORD, CONNECTICUT.

CONNECTING DEVICE.

1,162,354.

Specification of Letters Patent. Patented Nov. 30, 1915.

Application filed April 27, 1915. Serial No. 24,235.

To all whom it may concern:

Be it known that I, HAROLD A. HART, a citizen of the United States, residing at Hartford, county of Hartford, State of Connecticut, have invented certain new and useful Improvements in Connecting Devices, of which the following is a full, clear, and exact description.

My invention relates to connecting devices and has for its object to produce a receptacle and plug which have engaging surfaces so constructed that the plug can be secured in and removed from the receptacle by a partial revolution.

It further has for its object to produce a device the plug of which can be used in receptacles already in use.

The following is a description of my invention, reference being had to the accompanying drawings, in which,—

Figure 1 shows a plan view of the base with the plug, minus the cap, inserted. Fig. 2 is a section on the line 2—2, Fig. 1. Fig. 3 is a diagram showing the relations of the threads on the plug. Fig. 4 is a perspective detail of the base showing the thread thereon. Fig. 5 is a perspective view of the threaded portion of the plug.

Referring more particularly to the drawings, 1 is a base block having securing ears 2, 2.

3 is a metallic shell within which is an interrupted or quartered screw threaded metallic portion 4. Located axially within the shell is an inner metallic terminal 5, mounted on the base block.

6 and 7 are binding posts electrically connected to the terminal 5 and the screw threaded portion 4, respectively, as shown in dots in Fig. 1.

The construction so far described, if the portion 4 were not quartered, would be substantially the old construction of base receptacles.

8 is a porcelain core for the plug. Mounted on this core is a metallic member 9 having interrupted or quartered screw threaded surfaces 10 and 11 presenting independent surfaces engaging the screw threads on the base as hereinafter described. Each of these surfaces has portions of a thread of the same pitch as the thread in the portion 4. In the form shown the threading on the plug is sectioned or interrupted by the recessed portions 12, 12. The core carries an axially located metallic contact piece 13

which is connected to an external circuit terminal 14. The metallic member 9 is electrically connected to a corresponding external circuit terminal 15. The external circuit terminals 14 and 15 are adapted to receive two plugs from an ordinary detachable cord, and constitute no part of my invention.

16 is a cap member secured in place by a screw passing through the same and the core and into the contact 13, and has the usual openings for the plugs connected to the removable cord.

With my plug and socket each having quartered threads the plug can be inserted into the receptacle by a longitudinal movement so that when the contact 13 is in engagement with the inner terminal 5 it can be tightened up by a partial turn, which causes the screw threads to engage and draw the contact 13 into closer engagement with the inner terminal 5 on the base block, thus establishing proper electrical connections between the binding posts 6, 7 and the clip terminals 14 and 15. This is a very simple and convenient arrangement for securing the plug in the base receptacle. I have found, however, that my improvement just described is open to the objection that unless the plug is held in a certain angular position when inserted longitudinally the thread of the plug will not engage with the thread of the base so as to properly secure the plug by a quarter turn of the plug. In order to remove this objection I provide the plug with a plurality of threads of the same pitch as the thread on the base and equally subdividing the engaging surface on the plug. With such a plurality of threads there is always a thread on the plug which is in position to easily engage the thread on the base receptacle, so that when the terminals 5 and 13 are brought into engagement with each other by a longitudinal movement of the plug a quarter turn of the plug will always secure the plug in proper position, as shown in Figs. 1 and 2. I have found that two such threads, 17, 18, are sufficient.

In a double threaded plug the threads, if complete, would be as shown in Fig. 3, the two threads being parallel and beginning at diametrically opposite points in the same plane, so that the two points lying in any plane perpendicular to the axis of the plug and belonging to different threads are at

diametrically opposite points relatively to said plug. Fig. 3 shows one of two threads in full lines and the other in dots.

In forming what I call interrupted or quartered screw threaded portions, I remove or recess parts of the members carrying those portions along paths parallel to the axis of the screw threaded body.

One advantage of my construction is that the new base receptacle can be used with the old style plug and the new plug can be used with the old style receptacle.

As will be evident to those skilled in the art my invention permits of various modifications without departing from the spirit thereof of the scope of the appended claims.

What I claim is:

1. In an electrical connecting device, the combination of a receptacle having a quartered internal screw thread and an axially located inner terminal, and a plug having a quartered screw threaded portion and an

end contact engaging said internal screw thread and inner terminal respectively, said quartered screw threaded portion having two parallel threads of substantially the same pitch as the said internal screw thread.

2. In an electrical connecting device, the combination of a receptacle having a quartered internal screw thread and an inner terminal, and a plug having a quartered screw threaded portion and an end contact for engaging said internal screw thread and inner terminal respectively, said quartered screw threaded portion having two parallel threads of substantially the same pitch as the said internal screw thread, the portions of said two threads lying in the same plane being at diametrically opposite points relatively to said plug.

HAROLD A. HART.
